8 Claims. (Cl. 167—87.1)

This invention is concerned with improvements in or relating to hair sprays.

It has been proposed to use water-soluble synthetic resins, e.g. half esters of copolymers of maleic anhydride, condensation products of formaldehyde with hydantoin substituted in the 5-position, N-vinyl-2-oxazolidone polymers, polymers of N-vinylpyrrolidone or its copolymers with vinyl acetate, polyvinylimidazole and panthenol in aerosol hair sprays.

These water-soluble synthetic resins effect a sufficient stiffening of the hair and impart gloss to it. They have however the important disadvantage that in the case of slightly greasy hair this looks unsightly and forms locks and when used in conjunction with water waves (waves prepared with the aid of water) these sag if the air is too humid.

It has been proposed to use water-insoluble resins, namely those which have been obtained by esterification of phthalic anhydride with pentaerythritol in aerosol hair sprays. These resins are however neither soluble in nor compatible with fats, so that in most cases they are not able to absorb the grease produced by the scalp and the gloss of the hair is lost because the surface of the hair becomes uneven.

We have now surprisingly found that certain polyester resins do not have these disadvantages and may be used to yield hair sprays which absorb grease excellently. Since they also form an even surface on the single hairs, even with very greasy hair, they impart a very good gloss to the treated hair. Due to their good fat solubility and fat compatibility it is also possible to use fatty substances in the hair sprays and thus produce very suitable hair sprays for dry hair. Moreover, the resins are odorless, clear and physiologically inert.

According to the invention there is provided a composition suitable for use as a hair spray comprising a synthetic resin of a melting point about 40° C. functioning as a hair setting compound, said synthetic resin being an esterification product of a phthalic acid (or an anhydride where such exists) and a dihydric alcohol, and a propellant and/or a perfume. The said dihydric alcohol is an alkane diol of 2 to 6 carbon atoms, an ether of a polyhydric alcohol having 3 to 6 hydroxy groups, in which the hydroxy groups in excess of two are etherified by alkyl groups of 1 to 3 carbon atoms, 4,4'-dihydroxydicyclohexylpropane or a mixture of any one of the aforementioned alcohol components with less than an equivalent amount with respect to the latter of a polyhydric alcohol containing at least 3 and at most 6 hydroxy groups.

The propellant is preferably a fluorohydrocarbon or a chlorofluorohydrocarbon in which even all of the hydrogen atoms may be substituted by halogen atoms, particularly the various chlorofluoromethanes. As propellant there is also suitable octafluorocyclobutane, if desired in admixture with isobutane, the proportion of which in the mixture may be between 25 and 33%.

The synthetic resin may be produced by reaction of

2

the above-mentioned acids with the above-mentioned dihydric alcohols, for example in an equivalent ratio from 1:0.9 to 1:1.4, preferably from 1:1 to 1:1.25. In general the esterification is preferably carried out until the resin has an acid value from 80 to 150, advantageously from 90 to 120. Such resins should be hard and non-tacky; thus they should have a melting point above 40° C., preferably above 45° C. In general they are distinguished by a good solubility in halogen-containing, especially chlorine-containing hydrocarbons, such as methylene chloride, and generally also in lower and higher alcohols.

The dihydric alcohol component of the resin preferably contains at least three carbon atoms bound to each other by carbon to carbon bonds. The alcohol component may be, for example, ethylene glycol, propanediol-1,2 or -1,3, butanediol-1,3 or butanediol-1,4, hexanediol-2,5, hexenediol-1,6 or a mixture of such alcohols, but preferably it is 2,2-dimethyl propanediol-1,3 or 4,4'-dihydroxydicyclohexylpropane. Homologues of this last-mentioned substance may also be used. As alcohol component there may also be used ethers of polyhydric alcohols in which the hydroxy groups in excess of 2 are etherified by short-chained aliphatic radicals such as methyl, ethyl, propyl or isopropyl but which ethers still contain 2 free hydroxy groups. According to a further preferred embodiment the synthetic resins may be modified inasmuch as the alcohol component used is a mixture of a dihydric alcohol with less than an equivalent portion with respect to the latter of a polyhydric alcohol containing at least 3 hydroxyl groups e.g. glycerol, trimethylethane, trimethylolpropane, pentaerythritol, sorbitol or mannitol. The polyhydric alcohol may be used in such modified polyester resins, for example in an amount up to 80 equivalent percent, preferably between 50 and 75 equivalent percent, calculated on the dihydric alcohol.

In addition to the synthetic resin the hair sprays according to the invention may also contain additives such as solvents and diluents.

Of course, in all instances mixtures of several compounds may be used instead of a single compound.

In order that the invention may be well understood the following examples are given by way of illustration only. In the examples parts are by weight unless otherwise stated.

Example 1

(a) A fat-free hair spray can be obtained by mixing the following raw materials to form a base:

	Parts
50 Synthetic resin prepared from 1 equivalent phthalic anhydride, about 0.7 equivalent 2,2-dimethyl-1,3-propanediol and about 0.4 equivalent pentaerythritol (acid value 100-110, melting point 45-50° C.)	2.50
55 Triethylcitrate	0.30
55 Perfume	0.50
55 Methylene chloride	30.00
55 Isopropanol	66.70
	100.00

(b) This base in admixture with a propellant is used to fill aerosol containers in the following proportion and order:

	Parts
65 Base	80
65 Propellant (monofluorotrichloromethane:disfluorodichloromethane 37:63)	75

Example 2

A fatty hair spray can be obtained from the following components.

(a) Base:	Parts
Synthetic resin (see Example 1)	2.80
Isopropylmyristate	1.50
Lanolin	0.50
Perfume	0.50
Methylene chloride	30.00
Isopropanol	64.70
	100.00

(b) Contents of aerosol:	Parts
Base	80
Propellant (see Example 1)	75

Example 3

In a similar manner to Examples 1 and 2 other polyesters also can be used which have been prepared from:

- (a) 148 parts of phthalic acid,
- (b) 30 parts of pentaerythritol, and
- (c1) 40 parts of ethylene glycol, or
- (c2) 50 parts of propanediol-1,2, or
- (c3) 60 parts of butanediol-1,3, or
- (c4) 157 parts of 4,4'-dihydroxydicyclohexylpropane.

These polyester resins have the following characteristic values

	(c1)	(c2)	(c3)	(c4)
Melting range (° C.)	46/51	52/58	52/58	75/83
Acid value	95-105	100-110	85-95	110-125
Viscosity of a mixture with the same amount of ethylene glycolmonoethyl ether at 20° C. (in cp.)	124	151	142	130
Solubility in ethyl alcohol	Nearly insoluble	Until 1:1.5	Until 1:1.2	As desired
Solubility in methylene chloride	As desired	As desired	As desired	As desired

Resins c1 and c4 were, for example, manufactured according to the following formulations.

(a) Fatty hair spray:	Parts
Synthetic resin c1 or c4	2.80
Isopropylmyristate	1.50
Paraffin oil	5.00
Lanolin refinery product	0.50
Perfume	0.50
Methylene chloride	40.00
Isopropanol	49.70
	100.00

The paraffin oil used was clear, nearly colorless and odorless and had a viscosity of 3-5 cp. The lanolin refinery product was a solid, slightly yellowish wax-like material of the dropping point 59-70° C., which only contained lanolin fractions soluble in cold ethanol, did not have an unpleasant odor and had a saponification number of 2 to 8.

The mixture (a) was filled into aerosol containers in the manner described in Example 1.

(b) Non-fatty hair spray:	Parts
Synthetic resin c1 or c4	2.40
Acetylbutylcitrate	0.45
Dimethylphthalate	0.15
Perfume	0.50
Isopropanol	66.50
Methylene chloride	30.00
	100.00

The mixture (b) was filled into aerosol containers in the manner described in Example 1.

What is claimed is:

1. A composition suitable for use as a hair spray com-

prising a carrier and an effective amount of a synthetic resin with a melting point above 40° C. and an acid number between 80 and 150 and functioning as a hair setting compound, said synthetic resin being an esterification product of an unsubstituted phthalic acid and a dihydric alcohol selected from the group consisting of (1) an alkane diol of 2 to 6 carbon atoms, (2) ethers of polyhydric alcohols having 3 to 6 hydroxy groups and in which the hydroxy groups in excess of two are etherified by alkyl radicals of 1 to 3 carbon atoms, (3) 4,4'-dihydroxydicyclohexylpropane, and (4) mixtures of any one of components 1 to 3 with less than an equivalent amount with respect to the latter of a polyhydric alcohol containing at least 3 and at most 6 hydroxy groups, the acid and the alcohol components being contained in the said resin in an equivalent ratio between 1:0.9 and 1:1.4.

2. A composition as claimed in claim 1, wherein the polyhydric alcohol is pentaerythritol.

3. A composition as claimed in claim 1, wherein said polyhydric alcohol component is used in the resin in an amount in the range from 50-75 equivalent percent calculated on the amount of dihydric alcohol.

4. A composition suitable for use as a hair spray comprising a synthetic resin of a melting point above 40° C. up to 83° C. functioning as a hair setting compound, said synthetic resin being an esterification product of at least one acid component selected from the group consisting of phthalic acid and phthalic anhydride with 4,4'-dihy-

droxydicyclohexylpropane and 50 to 75 equivalent percent, calculated on the amount of dihydric alcohol, of pentaerythritol, said esterification product containing the acid and the alcohol component in an equivalent ratio between 1:1 and 1:1.25 and having an acid number between 90 and 120, and said hair spray composition also containing a perfume and a propellant.

5. A composition suitable for use as a hair spray comprising an effective amount of a synthetic resin with a melting point above 40° C. up to about 83° C. functioning as a hair setting compound, said synthetic resin being an esterification product of at least one acid component selected from the group consisting of phthalic acid and phthalic anhydride with at least one dihydric alcohol selected from the group consisting of (1) an alkane diol of 2 to 6 carbon atoms, (2) ethers of polyhydric alcohols having 3 to 6 hydroxy groups and in which the hydroxy groups in excess of two are etherified by alkyl radicals of 1 to 3 carbon atoms, and (3) 4,4'-dihydroxydicyclohexylpropane, and (4) mixtures of any one of components 1 to 3 with less than an equivalent amount with respect to the latter of a polyhydric alcohol containing at least 3 and at most 6 hydroxy groups, and a propellant comprising a halogenated hydrocarbon, said halogens being selected from the group consisting of (A) fluorine and (B) chlorine and fluorine, the acid and the alcohol components being contained in the said resin in an equivalent ratio between 1:0.9 and 1:1.4.

6. A composition suitable for use as a hair spray comprising a carrier and an effective amount of a synthetic resin with a melting point above 40° C. up to about 83° C. functioning as a hair setting compound, said synthetic resin being an esterification product of at least one acid component selected from the group consisting of phthalic acid and phthalic anhydride with at least one dihydric

alcohol selected from the group consisting of (1) an alkane diol of 2 to 6 carbon atoms, (2) ethers of polyhydric alcohols having 3 to 6 hydroxy groups and in which the hydroxy groups in excess of two are etherified by alkyl radicals of 1 to 3 carbon atoms, (3) 4,4'-dihydroxydicyclohexylpropane, and (4) mixtures of any one of components 1 to 3 with less than an equivalent amount with respect to the latter of a polyhydric alcohol containing at least 3 and at most 6 hydroxy groups, the acid and the alcohol components being contained in the synthetic resin in an equivalent ratio between 1:1 and 1:1.25 and the synthetic resin having an acid number between 90 and 120.

7. A composition as claimed in claim 1, wherein the carrier is a propellant and wherein the synthetic resin has a melting point above 45° C. and the alcohol component thereof contains at least 3 carbon atoms.

8. A composition suitable for use as a hair spray comprising a synthetic resin with a melting point above 40° C. up to about 83° C. functioning as a hair setting compound, said synthetic resin being an esterification prod-

uct of at least one acid component selected from the group consisting of phthalic acid and phthalic anhydride with 2,2-dimethyl-1,3-propanediol and 50 to 75 equivalent percent, calculated on the amount of dihydric alcohol, of pentaerythritol, said esterification product containing the acid and the alcohol component in an equivalent ratio between 1:1 and 1:1.25 and having an acid number between 90 and 120, and said hair spray composition also containing a perfume and a propellant.
